(57) **CLAIM**

I claim the ornamental design for a roof for a utility vehicle, as shown and described.

DESCRIPTION

FIG. 1 is a left, front perspective view of a roof for a utility vehicle of the present invention;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines illustrate portions of the roof for a utility vehicle which form no part of the claimed design.
